UNITED STATES PATENT OFFICE.

JOSEPH HENDERSON BEHEE, OF LEAVENWORTH, KANSAS, ASSIGNOR TO M. BURNS & CO., OF SAME PLACE.

FURNACE.

SPECIFICATION forming part of Letters Patent No. 417,465, dated December 17, 1889.

Application filed May 19, 1888. Serial No. 274,369. (No model.)

To all whom it may concern:

Be it known that I, JOSEPH HENDERSON BEHEE, of Leavenworth, in the county of Leavenworth and State of Kansas, have invented a new and Improved Furnace, of which the following is a full, clear, and exact description.

The object of this invention is to increase the radiating-surface of the furnace, and at the same time to so arrange the several parts of the furnace that the draft may be regulated to suit the requirements of the weather.

A further object of the invention is to so arrange the several flues that they may be quickly and readily cleaned, such cleaning of the flues being absolutely essential where soft coal is burned.

Reference is to be had to the accompanying drawings, forming a part of this specification, in which similar figures of reference indicate corresponding parts in all the views.

Figure 1 is a face view of my improved furnace. Fig. 2 is a cross-sectional view of the same, the view being taken on line xx of Fig. 1. Fig. 3 is a sectional plan view on line yy of Fig. 2, parts being broken away. Fig. 4 is a sectional plan view on line zz of Fig. 2. Fig. 5 is a front view of the furnace, the front wall being removed and the flues being shown in partial section; and Fig. 6 is a view taken in the direction of the arrow a , Fig. 5, the front wall and the lower flue-walls being shown in section.

In the drawings above referred to, 10 represents the fire-pot; 11, the grate; 12, the receiving-chute, which is normally closed by a door 13, the receiving-chute extending outward through the front wall 14, as shown.

From the top of the fire-pot there leads a pipe 16, which joins the smoke-stack 18, and in this pipe 16 there is mounted a damper 17, the stem of which extends outward through the masonry in which the furnace is set, and is there provided with a handle 2, the arrangement being such that if the damper be drawn outward the draft will be direct from the fire-pot to the smoke-stack, and this damper should always be drawn out when a fresh fire is made, or when it is de-

sired to kindle up a fire that has become almost extinguished.

After the fire has been lighted the damper 17 is closed, and then the products of combustion pass through two pipes 20 downward to upper flues 21, the pipes 20 entering the flues 21 at their forward ends. From the flues 21 the products of combustion enter flues 22 through openings 3, and from the flues 22 the products pass on through apertures 4 into a central return-flue 24, which is in direct communication with the stack 18. In this way it will be seen that a great expanse of metal is heated, and the cold air, which is delivered from the chamber about the fire-pot in the usual manner and enters through a flue 26, must necessarily pass over this heated surface. At times a less amount of heating-surface would be required, and to cut off a portion of the surface and at the same time to increase the draft of the furnace I provide dampers 5, which are hinged in position, so that they may be moved to close the apertures 3 and open a way so that the products of combustion will pass through other apertures 6, and thence directly through the smoke-stack.

The flues 21 and 22 are provided with doors 30, (see Fig. 1,) which doors may be swung open when it is desired to clean out the flues, a similar door 31 being arranged in connection with the central return-flue 24. Just above this central return-flue 24 there is an ash-chamber 32.

Having thus fully described my invention, I claim as new and desire to secure by Letters Patent—

1. A furnace consisting in a fire-pot, an ash-pit, an outlet-pipe 16, provided with a damper, a vertical stack 18, into which said pipe discharges, upper and lower horizontal flues 21 22 at opposite sides of the ash-pit communicating at their rear ends, and a central horizontal flue 24 under the ash-pit, and with the forward end of which the lower flues 22 communicate, said central flue opening at its rear end into the lower end of the stack, substantially as set forth.

2. The combination, in a furnace, with the fire-pot having flues leading downward from

the upper portion thereof, opposite horizontal flues into which the first-named flues discharge, and a central flue communicating with the side flues, of a stack 18, communicating at its lower end with the rear ends of said central and side flues, dampers 55, controlling the openings between the side flues and the stack, and a direct-draft flue lead-

ing from the upper end of the furnace into the stack and provided with a damper, substantially as set forth.

JOSEPH HENDERSON BEHEE.
